UNITED STATES PATENT OFFICE.

FRANZ CARL BENEDECT, OF VIENNA, AUSTRIA-HUNGARY, ASSIGNOR OF ONE-HALF TO
ALOIS LÖWY, OF VIENNA, AUSTRIA-HUNGARY.

BLOTTING-CRADLE.

1,079,206.

Specification of Letters Patent. Patented Nov. 18, 1913.

Application filed November 16, 1912. Serial No. 731,914.

To all whom it may concern:

Be it known that I, FRANZ CARL BENEDECT, subject of the Emperor of Austria-Hungary, residing at Pappenheimgasse 8, 5 Vienna, XX, in the Province of Lower Austria and Empire of Austria-Hungary, have invented certain new and useful Improvements in Blotting-Cradles, of which the following is a specification.

10 The object of my invention is a blotting cradle, the blotting plate of which can be conveyed from the curved into a flat shape, so that it may be used as a rule for tracing lines.

15 In the annexed drawings an example of the blotting cradle is illustrated in vertical section (Figure 1) and in plan view (Fig. 2). Figs. 3 and 4 show a modification.

20 The bow part *b* which is provided with blotting paper *a*, may be conveyed from the curved into the flat shape, as is represented in Fig. 1 by dotted lines. The stretched bow part which may be provided with a longitudinal scale, can then be used as a 25 common rule for drawing lines. The stretching or flattening of the part *b* is effected according to the present invention by moving the handle button *c* along a guide bar *d* secured in the middle of the 30 part *b*. The button *c* will be held in position by a spring lever *f* which engages a notch in the guide bar *d*. The lever *f* is to be released either by hand and merely by 35 pressing upon the lever end projecting from the button *c* or in any other suitable manner. To the button *c* are hinged two stretching arms *g*, the other ends *h* of which are movably connected with the back of the bow part *b*. If now the handle button *c*, 40 being in the position illustrated by full lines, will be released and moved down the guide bar, until the lever *f* will engage a second notch, as is represented by dotted lines, the bow part *b* will be stretched or 45 flattened by the stretching arms *g*. The back of the bow part *b*, which is provided with the two clamping devices *k* for the blotting papers *a* and carries a soft layer *i* of felt or the like to support the papers *a*,

50 may be constituted by several steel sheets *l* which can slide in relation to each other. The uppermost sheet *l* for example is provided with a slot *m*, through which the lower end *h* of the respective stretching

arm *g* passes into the back and will be slid- 55 ably held therein.

In case the bow part *b* has the tendency to spring into the flat shape, the transferring from the curved into the flat shape will be effected only by releasing the bow 60 part *b* being held in curved shape. The arms *g* may be simply pivotally connected to the back of the blotting cradle, as shown in Fig. 3. The handle button *c* may also be arranged so as to fix the stretching device 65 merely by turning the said button. For this purpose the latter may be provided for example with an inner lug or screw *p* (Fig. 3) projecting into a slot *q* of the guide bar *d*. The said slot terminates at the lower 70 end or as shown at the lower and upper end in a short transverse or horizontal part *r*. If now the button *c* will be turned when it is in respectively its lower or upper end position, the button and also the 75 part *b* will be fixed in the flat or curved condition.

Claims.

1. A blotter of the character described, comprising a flexible plate, means on the 80 plate to support a blotter, a stem extending from the flexible plate, and means operable on the stem and connected to the plate for holding the plate curved, when in one position and permitting said plate to assume a 85 flat shape when said means are in another position.

2. A blotter of the character described, comprising a flexible plate, means on the 90 plate to support a blotter, a stem extending from the plate, a slidale element on the stem, members extending from the slidale element to the plate, whereby when the sliding element is in one position the flexible plate will be curved and when said element is in another position the flexible plate will be flat, and means for holding the slidale element in locked position on the stem 95 when in one position.

3. A blotter of the character described, 100 comprising a flexible plate, a stem extending therefrom, a slidale element on the stem, arms pivoted to the slidale element and engaging the plate, and a locking device carried by the slidale element to lock the 105 latter to the stem whereby to hold the plate in a curved or a flat position.

4. A blotter of the character described

comprising a base comprised of a plurality of flexible plates, means including an element slidable with reference to the base and oppositely extended arms between the slid- 5 able element and the base to set the latter in a curved or flat position, and means for locking the slidable element in either position.

5. A blotter of the character described, 10 comprising a flexible plate, a stem extending from the plate and formed with notches, a slidable element mounted on the stem, two arms pivoted to the slidable element, the

outer ends of said arms engaging the flexible plate, a locking latch pivoted to the sliding element and adapted to engage with either of the notches in the stem to hold the plate in a flat or a curved position. 15

In testimony whereof I have hereunto set my hand in presence of two subscribing 20 witnesses.

FRANZ CARL BENEDICT.
